UNITED STATES PATENT OFFICE.

ROBERT W. DAVIS, OF CHICAGO, ILLINOIS.

WASHING-MACHINE.

1,119,578.

Specification of Letters Patent.

Patented Dec. 1, 1914.

Application filed October 3, 1912. Serial No. 723,769.

To all whom it may concern:

Be it known that I, ROBERT W. DAVIS, a prospective citizen of the United States, residing at Chicago, in the county of Cook 5 and State of Illinois, have invented certain new and useful Improvements in Washing-Machines, of which the following is a specification.

This invention relates to a machine for 10 washing clothes, and fabrics in general, which is designed to be operated by hand or power.

In the present invention, it is sought to produce a machine combining in its structure 15 the fewest possible parts; mechanism for automatically feeding clothes into contact with washing members; mechanism for operating washing members in conjunction with one another and relatively adjustable 20 in speed of movement; mechanism for rubbing over the clothes soap or any other suitable saponaceous body; and mechanism for dislodging clothes from between the washing members after the same have been 25 cleansed.

It is sought further in this invention to arrange washing members with actuating mechanism therefor located above the water line to eliminate joints which would have to 30 be packed to prevent an outflow of liquid from within the machine.

The invention consists further in features 35 of construction and combination of parts hereinafter described and claimed.

In the drawings, Figure 1 is a longitudinal vertical section through the washing machine as a whole; Fig. 2 is a plan view 40 with the cover removed; Fig. 3 is an enlarged detail in plan of the mechanism for imparting rotary movement to one of the washing members; Fig. 4 is a side elevation 45 of the same; Fig. 5 is a perspective view of a portion of the mechanism employed to feed the clothes or fabric into engagement with the washing members; and Fig. 6 is an enlarged detail in cross section of the trough or receptacle in which soap or other suitable saponaceous body is retained in engaging position adjacent the clothes to be 50 washed.

The machine comprises a tank 7 of watertight construction adapted to retain therein

a quantity of liquid, the preferred level of said liquid being indicated in Fig. 1, and an outlet is provided in the valve 8 adjacent 55 the bottom of the tank. In order that the whole operation of washing may be effected with the least amount of splashing or spilling of liquid, a cover 9 is arranged over the tank to be secured by any suitable means. 60

Mounted within the tank is a drum 10 adapted to revolve about a shaft 11 suitably secured at either end within journals 12 attached to the inside of the tank. The exterior of said drum is formed of a series of 65 circumferential corrugations 13, upon the raised portions of which are interspersed steps or notches 14 to be more fully herein-after explained. Positioned adjacent the drum and preferably immediately thereover 70 is a longitudinally extending arcuate shaped rubbing member 15 preferably transversely corrugated, and adapted to be moved lengthwise across the upper face of the drum with a reciprocating movement. 75 Mechanism for imparting this reciprocating movement is provided in the rod 16, having one end thereof pivotally secured to the rubbing member, and the other end thereof extending through a slot 17 formed in the side 80 of the tank and above the water line, to connect with the crank end 18 of a rotary shaft 19 suitably journaled as at 20, and to one end of which is preferably secured a fly 85 wheel 21 to impart a desirable amount of momentum to the shaft 19. A suitable crank may be provided upon the fly wheel 21 in case it is wished to operate the machine by hand, but if the machine is designed to be operated by power, a belt or 90 other suitable means of transmission may be connected as to the wheel 21. The arcuate-shaped rubbing member 15, as is best shown in Fig. 1, is located above the water line in the tank, so that the arm 16 which extends 95 through to the outside of the tank is above the water line and is free to move within the slot 17 without danger of liquid passing therethrough.

Means for reinforcing the rubbing member and guiding the reciprocation thereof in a plane of predetermined proximity to the drum are provided in the member 22 which extends longitudinally of the rubbing mem-

ber; the ends of this member project beyond the rubbing member, one through the slot 17 and the other through a similarly formed slot 23 in the opposite side of the tank. 5 These slots which are preferably elongated are so positioned that the ends of the members 22 which lie therein tend to maintain the rubbing member normally in an operating plane close to but free from the drum. 10 The position of the rubbing member with respect to the drum may be shifted, however, according to the quantity of fabric passing between it and the drum. Normally it is held in close engagement with the drum through tension means 24 secured at the end 15 of the guide member upon the outside of the tank; but when a considerable amount of material is fed between the drum and rubbing member, the rubbing member may yield 20 under the pressure and against the tension of the springs 24 to operate in a plane farther away from the drum, this being possible because the slots 17 and 23 are designed to be sufficient in length to permit of the 25 ends of the member 22 shifting therein. In operation, the rubbing member will be reciprocated back and forth over the drum many times before the drum has turned a complete revolution, a saponaceous substance 30 hereinafter described meanwhile engaging with the clothes being fed between the washing members and producing suds in quantity sufficient to insure a thorough cleansing. Further means for guiding the reciprocatory 35 movement of the rubbing member is provided in the arms 25 and 26 suitably arranged within the tank and having the ends 27 thereof pivotally secured adjacent the ends of the rubbing member, and the other 40 ends 28 thereof secured as to brackets 29 positioned against the sides of the tank. The arm 26 is formed in the shape of a bell crank, having its crank end 30 provided with a series of openings 31 within any one 45 of which the end 32 of a pawl 33 may be secured, the acting end 34 of which is adapted to engage with a ratchet wheel 35 formed on one end of the drum. In order to prevent lateral displacement of the pawl 33 from 50 the ratchet 35, the acting end of the pawl is formed with ears 35^a adapted to overlie the ratchet wheel on either side thereof. The pawl may be adjusted with respect to the bell crank in such manner as to provide a 55 number of relative speeds for the drum, so that it is possible to regulate the movement of the washing member according to the character of the fabric to be washed.

60 The clothes or fabric to be washed are placed in the tank upon feeding bars 36 attached upon a crank shaft 37, the cranks of which throughout the length of the shaft are set alternately at about 180° to each

other. The crank shaft 37 is operated at one or both ends as by means of connecting rods 38 operating from a crank shaft 39 similar to the shaft 37 which may be driven at one end as by means of a chain 40 engaging with a sprocket 41 formed on the crank shaft and connected with a sprocket 70 42 formed on one end of the drum. A series of pins or projections 43 are formed on the engaging surfaces of the feeding bars and as the same are successively actuated by the crank shafts 37 and 39, the clothes lying 75 thereupon are fed forwardly and upwardly by the said members and over their curved ends 44 positioned adjacent the drum 10, so that the clothes are laid upon the drum and beneath the rubbing member 15. 80

A trough or receptacle 45 is carried by the rubbing member adjacent one edge thereof, adapted to retain therein a saponaceous body 46, such as soap, a portion 47 of which may protrude through an opening 48 85 formed in the lower portion of said trough to engage with the fabrics to be washed. Since the trough is moved back and forth with each reciprocation of the rubbing member, it follows that the clothes are thoroughly rubbed by the soap prior to being passed between the washing members. The trough as illustrated in Fig. 6 is designed to hold soap chips or cakes, but with suitable modification may be arranged to hold saponaceous substances in other forms. 90

The steps or notches 22 formed on the raised corrugated portion of the drum are arranged each to present a surface at right angles to the periphery of the drum to assist 100 in carrying the clothes or fabric over the drum and beneath the rubbing member. A series of teeth 49 positioned preferably close to the under side of the drum and which engage only the recessed portions of the corrugations formed thereon serve to dislodge 105 the clothes when they have been carried around upon the drum and are cleansed; these teeth are secured upon a partition 50 arranged to prevent clogging of the clothes 110 with the feeding mechanism.

The washing machine which has been described is seen to be compact and free from complication of parts. It is furthermore arranged in such manner that the driving 115 means are located above the water line, so as to eliminate joints which would otherwise have to be packed. Except for the driving shaft upon the outside of the tank, all of the parts are housed under cover, so that 120 little or no danger is presented to an operator who may stand close by.

I claim:

In a washing machine, the combination of a circumferentially corrugated rotatable 125 drum, a transversely corrugated rubbing

member arranged to be reciprocated longitudinally of said drum, means for reciprocating said rubbing member, means for intermittently rotating said drum actuated by
5 each alternate movement of said rubbing member, means for automatically feeding clothes between said drum and rubbing

member, and means for dislodging the clothes from the drum after the washing operation, substantially as described.

ROBERT W. DAVIS.
